(57) CLAIM

The ornamental design for a cat shelter, as shown and described.

DESCRIPTION

FIG. 1 is a front, top, right perspective view of a cat shelter, showing my new design;

FIG. 2 is a left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of FIG. 1; and,

FIG. 10 is a partial enlarged view of FIG. 4.

The dashed broken lines in the figures are for the purposes of illustrating portions of the cat shelter and form no part of the claimed design.

The short-short-long dashed broken lines immediately adjacent to the claim area in the FIGS. 1 are for the purposes of illustrating the boundaries of the cat shelter, and form no part of the claimed design.

The dash-dot-dash broken lines are for notating enlarged views and form no part of the claimed design.
